UNITED STATES PATENT OFFICE.

ALBERT H. DEAN AND CHARLES A. HOTCHKISS, OF BRIDGEPORT, CONN.,
ASSIGNORS TO IVES, BLAKESLEE & CO., OF SAME PLACE.

TOY PISTOL.

SPECIFICATION forming part of Letters Patent No. 294,450, dated March 4, 1884.

Application filed December 29, 1883. (No model.)

To all whom it may concern:

Be it known that we, ALBERT H. DEAN and CHARLES A. HOTCHKISS, of Bridgeport, in the county of Fairfield and State of Connecticut, have invented a certain new and useful Improvement in Toys, of which the following is a specification.

The toy which is illustrated in the accompanying drawings as an example of this improvement has a handle shaped like the handle of an ordinary pistol, a receptacle made in the shape of an egg, a barrel or a like article forward of the handle, a cover for the receptacle, a movable device within the receptacle, and a hammer-like contrivance whereby the said movable device may be forced out of the receptacle aforesaid.

In the drawings, Figure 1 is a side view of a toy embodying our improvement, and Fig. 2 is a longitudinal section of the same.

Similar letters of reference designate corresponding parts in both figures.

A designates a handle shaped very much like the handle of an ordinary pistol. Forward of this handle is a receptacle, B, which, as here shown, is shaped like an egg. This receptacle B and the handle A may be cast together in two longitudinal halves provided with interlocking projections and recesses, and fastened together by screws or rivets. At the forward end of the receptacle is a cover, C, which is hinged to the receptacle near the bottom by means of a pin, a, passing through lugs b c, extending from the receptacle and cover, respectively. This cover is shaped like the end of an egg. The meeting edges of the receptacle and cover are made irregular, so as to resemble a break in an egg-shell.

D designates a device here shown as made in the shape and configuration of a bird. It may be cast hollow. At the rear it has a shank, which extends through the rear of the receptacle B, and at the end is connected by a pin, d, to a contrivance, E. This contrivance is pivoted to the handle A, like the hammer of a pistol, and is similarly impelled forward

by a spring, F. A trigger, G, pivoted to the handle A, and combined with a spring, H, controls the action of the hammer-like contrivance E. This hammer-like contrivance is 50 so formed as to resemble a rooster. There may be a seat for a cap or fulminate at the rear of the receptacle B, and the device E may strike a cap or fulminate placed in or on the same. When the hammer-like contrivance E is drawn back, the device D will be drawn into the receptacle B, and the cover C will then be closed. By pulling the trigger G the hammer-like contrivance will be released, whereupon it will force the device D forward, 60 so that it will open the cover and protrude. A cap or fulminate may also be exploded.

Instead of representing an egg, the receptacle B may represent a barrel or analogous article, and the device D, instead of representing a bird, may represent any other object. We desire, also, to suggest that the receptacle B may represent the shell of a turtle, and the device D the head and front legs of a turtle.

What we claim as our invention, and desire 70 to secure by Letters Patent, is—

1. In a toy, the combination of a receptacle representing an egg, or a barrel or analogous article, a cover therefor, a device representing a bird or other object, a hammer-like contrivance for forcing the said device forward, 75 so that it will open the cover and protrude, and a trigger, substantially as specified.

2. In a toy, the combination of a receptacle representing an egg, a barrel, or analogous article, a cover therefor, a device representing a bird or other object, a hammer-like contrivance, and a shank on the device for connecting it with the hammer-like contrivance, so arranged that the device may receive a reciprocating motion lengthwise of the receptacle to open the cover.

ALBERT H. DEAN.

CHARLES A. HOTCHKISS.
